UNITED STATES PATENT OFFICE

160,375

KITCHEN TONGS

Walter W. Edlund, Burlington, Vt.

Application August 11, 1948, Serial No. 148,052

Term of patent 3½ years

(Cl. D44—4)

To all whom it may concern:

Be it known that I, Walter W. Edlund, a citizen of the United States, and a resident of Burlington, in the county of Chittenden and State of Vermont, have invented a new, original, and ornamental Design for Kitchen Tongs, of which the following is a specification.

Reference is had to the accompanying drawings forming part thereof, in which:

Fig. 1 is an end elevational view of the kitchen tongs, showing my new design, and

Figures 2 and 3 are views looking at opposite sides of the tongs shown in Fig. 1.

I claim:

The ornamental design for kitchen tongs, as shown.

WALTER W. EDLUND.
